CLAIM

The ornamental design for a snow groomer, as shown and described.

DESCRIPTION

FIG. 1 is a top front perspective view of a snow groomer showing our new design, the broken line showing of portions of the snow groomer in FIGS. 1-7 is included for the purpose of illustrating environmental structure only and forms no part of the claimed design.

FIG. 2 is a rear perspective view thereof.

FIG. 3 is a front view thereof.

FIG. 4 is a rear view thereof.

FIG. 5 is a left side view thereof.

FIG. 6 is a right side view thereof; and,

FIG. 7 is a top plan view thereof.

1 Claim, 7 Drawing Sheets
